A. P. GRAHAM
INVENTOR
BY Victor J. Evans

ATTORNEY

UNITED STATES PATENT OFFICE.

ARCHIBALD P. GRAHAM, OF ELKHORN, WISCONSIN.

MOLD FOR FORMING SAXOPHONE MOUTHPIECES.

Application filed June 10, 1922. Serial No. 567,312.

To all whom it may concern:

Be it known that I, ARCHIBALD P. GRAHAM, a citizen of the United States, residing at Elkhorn, in the county of Walworth and State of Wisconsin, have invented new and useful Improvements in Molds for Forming Saxophone Mouthpieces, of which the following is a specification.

This invention relates to saxophone mouthpieces and the manner of forming them.

Heretofore it has been the practice to turn out the mouthpieces for saxophones, on lathes, or analogous machines, making the mouthpieces quite expensive and requiring considerable time and labor for properly shaping them, and it is an object of this invention to provide suitable molds and cores by means of which the mouthpieces may be formed by the die casting process, thereby materially decreasing the expense contingent with the forming of the mouthpiece as well as resulting in savings in time and labor.

Another object of this invention is to provide a saxophone mouthpiece as specified which has a separate sleeve inserted in a portion of the body at its outlet end for constricting the outlet and particularly adapting the mouthpiece for construction by die casting.

A still further object of the invention is to provide a novel form of core and plunger structure particularly designed to facilitate the die casting of the mouthpieces and constructed to maintain absolute accuracy in the molding of the mouthpieces.

Other objects of the invention will appear in the following detailed description taken in connection with the accompanying drawings wherein:

Fig. 1 is a longitudinal section through a mold and saxophone mouthpiece formed therein showing the improved core and plunger in side elevation taken on the line 1—1 of Fig. 2.

Fig. 2 is a top plan of a saxophone mouthpiece and core showing it in position in the mold.

Fig. 3 is an end elevation of the core.

Fig. 4 is a bottom plan of the plunger used in connection with the core in the molding of the mouthpieces.

Fig. 5 is a section through a mold and core showing the formation of the sleeve

which is inserted into the body of the mouthpiece taken on the line 5—5 of Fig. 6.

Fig. 6 is a cross section taken on the line 6—6 of Fig. 5.

Fig. 7 is a view partly in section and partly in side elevation of a saxophone mouthpiece constructed in accordance with this invention.

Referring more particularly to the drawings, a saxophone mouthpiece 1, is shown, which saxophone mouthpiece is die cast, of hard rubber, bakelite, or analogous material such as commonly used in the construction of mouthpieces for saxophones and in forming the mouthpiece 1, a mold 2 of any approved type, or construction such as used in die casting, is utilized; which mold is provided with a chamber 3 properly shaped to provide the desired configuration to the mouthpiece 1, having the flat surface 4 to provide the deck or face 5 of the mouthpiece 1, and further provided with the rounded relatively large portion 6 for providing the rest of the mouthpiece. The bore or inner configuration of the mouthpiece 1 is provided by the use of a core 7 which is constructed preferably of brass or analogous metal and has a substantially cylindrical portion 8 which is carried by the handle portion 9, and as clearly shown in Fig. 1 of the drawings the substantially cylindrical portion 8 gradually increases in diameter towards the handle portion 9 so as to permit the easy withdrawal of the core 7 from the mold 2 and formed mouthpiece 1. The throat 10 of the mouthpiece 1 is formed by a plunger 11 which is constructed of brass or analogous material and is shaped, in plan, as clearly shown in Fig. 4 of the drawings to provide the desired shape to the throat 10. The corner 12 of the plunger 11 is beveled slightly as clearly shown in the drawings so as to provide the proper shape to the inner wall of the throat at its open edge and for proper alignment with the inclined edge 13 of the reduced throat forming end 14 of the core 7. The upper surface of the reduced throat forming end of the core 7 is flat, and the plunger 11 rests thereon during the molding of the mouthpiece 1.

It is to be understood that in constructing the core 7 and plunger 11 that proper allowance is made for shrinkage in the material of which the mouthpiece is formed as is usual in the construction of patterns.

It is necessary, to obtain the proper results from the mouthpiece that the outlet end of the bore 15 of the mouthpiece be of smaller diameter than the inlet end and it will be readily understood that should the core 7 be constructed to provide this reduced size of the bore it would be impossible to withdraw the core after the mouthpiece had been formed, and to provide this reduced size of the bore, a sleeve 17 is provided the bore of which is of uniform diameter throughout while the outer diameter of the sleeve gradually increases towards one end, as clearly shown in Fig. 5 of the drawings so as to permit the sleeve to properly fit in the bore 15 of the mouthpiece 1. The sleeve 16 may likewise be formed by die casting utilizing a mold 17 through which a cylindrical core 18 is inserted as shown in Figs. 5 and 6 of the drawings.

From the foregoing description taken in connection with the accompanying drawings it will be apparent that a saxophone mouthpiece has been provided which will particularly lend itself to molding and also that proper cores have been devised which will permit the molding of the saxophone mouthpiece by what is commercially known as the die casting process thereby permitting the construction of the mouthpieces at a much lower cost and with much less labor than it is possible to produce them by turning or the present approved method of constructing them.

It is, of course, to be understood that the invention may be constructed in other manners and the parts associated in different relations and, therefore, I do not desire to be limited in any manner except as set forth in the claims hereunto appended.

Having thus described my invention what I claim is:

1. The combination with a die cast mold for forming saxophone mouthpieces, of a metal core removably inserted into said mold and being shaped to provide the interior configuration of a saxophone mouthpiece, said core having a reduced throat forming end, and a metal plunger adapted for insertion into said mold and for resting upon said reduced end to provide the throat opening.

2. The combination with a die cast mold for forming saxophone mouthpieces, of a

metal core removably inserted into said mold and being shaped to provide the interior configuration of a saxophone mouthpiece, said core having a reduced throat forming end, a metal plunger adapted for insertion into said mold and for resting upon said reduced end to provide the throat opening, said core having a handle formed thereon remote from the reduced throat forming end, and a cylindrical portion gradually increasing in diameter from the reduced end to said handle portion.

3. The combination with a die cast mold for forming saxophone mouthpieces, of a metal core removably inserted into said mold and being shaped to provide the interior configuration of a saxophone mouthpiece, said core having a reduced throat forming end, a metal plunger adapted for insertion into said mold and for resting upon said reduced end to provide the throat opening, said core having a handle formed thereon remote from the reduced throat forming end, and a cylindrical portion gradually increasing in diameter from the reduced end to said handle portion, the outer inner corner of said plunger being cut away to conform to the inclined surfaces of said reduced end.

4. The combination with a die cast mold for forming saxophone mouthpieces, of a metal core removably inserted into said mold, said core having a reduced throat forming end, a handle formed upon the core remote from the reduced throat forming end, and said core having a cylindrical portion gradually increasing in diameter from said reduced portion to said handle portion.

5. The combination with a die cast mold for forming saxophone mouthpieces, of a metal core removably inserted into said mold, said core having a reduced throat forming end, a handle formed upon the core remote from the reduced throat forming end, and said core having a cylindrical portion gradually increasing in diameter from said reduced portion to said handle portion, one surface of said reduced portion being flattened, and a metal plunger adapted for insertion into said mold and for resting upon said flattened surface.

In testimony whereof I affix my signature.

ARCHIBALD P. GRAHAM.
